UNITED STATES PATENT OFFICE.

MARY CHASE BARON, OF HAMPDEN MEADOWS, RHODE ISLAND.

BROODER.

Application filed August 26, 1920. Serial No. 406,185.

To all whom it may concern:

Be it known that I, MARY CHASE BARON, a citizen of the United States, residing at Hampden Meadows, in the county of Bristol and State of Rhode Island, have invented 5 certain new and useful Improvements in Brooders, of which the following is a specification.

This invention relates to certain new and 10 useful improvements in brooders or artificial mothers for chickens.

One of the objects of this invention is the provision of simple and effective means whereby the curtains which inclose the 15 brooding space may be readily removed from inclosing position when desired.

A further object of this invention is the provision of means whereby the area of the brooding space may be readily enlarged beyond 20 its normal size to accommodate a greater number of chicks.

With these and other objects in view, the invention consists of certain novel features of construction, as will be more fully described, and particularly pointed out in the appended claims.

In the accompanying drawings:

Figure 1 is a plan view of my improved brooder, illustrating the slidable plates as 30 mounted on the inclined edge surface of the hood member, and in position to enlarge the brooding space within.

Figure 2 is a vertical longitudinal section of the structure shown in Figure 1.

Figure 3 is a top view of the brooder, showing the curtain-supporting rods as arranged in sections about the periphery of the brooder hood and each rod section being pivotally mounted at one end to be 40 swung out on its pivot end as shown in dotted lines.

Figure 4 is a detail illustrating means for pivoting the ends of the curtain-supporting rods.

With reference to the drawings, 10 designates the heater member of the brooder, which is preferably formed of a tank in which water is contained, the same being heated by means of a burner 11 located at 45 the lower end of the drop leg 12 in which the water therein contained is caused to circulate rapidly, which circulating action is facilitated by means of a jacket 13 about the heat flue 14, the body portion of this

heated tank being preferably of extended 55 area with its center portion 15 removed to prevent undue heating in the middle of the brooder and also to stimulate a circulation of air through the brooding chamber.

Over this heated tank I have mounted a 60 hood 16 having its peripheral edge 17 set on an incline or flaring outwardly for two reasons: first, to assist in deflecting the heat at the under side of the hood downwardly into the brooding chamber below; and second, for the purpose of supporting extension 65 plates 18 which may be formed in sections and slid or moved downwardly and outwardly thereon to extend or enlarge the area of the brooding space beneath, thus 70 providing accommodations for a larger family of little ones than could be accommodated by a hood of the original diameter.

These enlarging plates may be connected to and supported on the inclined periphery 75 of the hood by any suitable means, but I have herein shown them secured thereto by bolts 19 passing outwardly from the main portion of the hood through the overlapping edges of the adjacent extension plate sections, and a wing nut 20 is threaded onto the end of each bolt for the purpose of binding the different sections in adjusted position, but any suitable means for securing these enlarging plate sections may be employed. 80

About the periphery of this hood, or the extending or enlarging plates thereof, curtains 21 of any suitable material may be suspended for the purpose of inclosing the 90 brooding space.

These curtains are preferably slashed at 22 on their lower edges to permit the chicks to pass in and out therethrough, and the curtains are also preferably provided with 95 openings 23 to permit the entrance of light and fresh air to the brooding space.

It is found in practice of advantage to be able to quickly withdraw different sections of these curtains for the purpose of inspecting and exposing the interior of the brooding chamber. 100

To accomplish this in a simple and effective way, I have provided a plurality of curtain rod sections 24 which are preferably 105 constructed of short sections of heavy wire, one end of each rod being turned upwardly as at 25, see Figure 4, to extend through the

upper and lower plates 26 of the bracket 27 forming a hinge for these rod sections.

A hook-shaped clip 28 is arranged to receive the free end of each rod member to support and retain it in operating position.

The curtains themselves are also made in sections and preferably double and of such material as thin oilcloth and the like, and the rod 24 is passed through a loop or hem 10 29 along the upper edge thereof by which arrangement when it is desired to withdraw or remove the curtain to expose a section of the brooding space within, it is only necessary to unhook the free end of the curtain 15 rod and swing it out, as illustrated in dotted lines in Figure 3. Any one or all of these sections may be operated to throw back the curtains and expose the entire brooding space when desired and as quickly close them 20 by simply swinging the rods inwardly and hooking their ends over their respective clips 28.

These curtain supporting rods may be either mounted on the edge of the hood 25 proper, as illustrated in Figures 3 and 4, or they may be mounted about the edge of the extending hood plates if desired as shown in Figures 1 and 2.

By the use of my improved construction 30 of brooder the operating size of the brooding space may be varied at will to accommodate broods of different sizes, and the inclosing curtains about the brooder may be readily moved to expose any desired section of the 35 interior of the brooder or the whole interior may be exposed at once if desired and the curtains as readily and quickly returned to inclosing position.

The device is extremely simple and practical in construction and effective in its operation.

The foregoing description is directed solely towards the construction illustrated but I desire it to be understood that I reserve the privilege of resorting to all the 45 mechanical changes to which the device is susceptible, the invention being defined and limited only by the terms of the appended claims.

50 I claim:

1. In a brooder, a heat-distributing member, a hood about said member, curtain supports about the periphery of said hood, curtains on said supports for inclosing the 55 brooding chamber, and said supports being shiftably mounted on the hood to move the

curtains bodily in a horizontal plane to open positions from closed position.

2. In a brooder, a heat-distributing member, a hood about said member, curtain supports pivotally mounted about the periphery of said hood, curtains on said supports for inclosing the brooding space, and said supports being adapted to be swung out on their pivoted ends in a horizontal plane to quickly expose the interior of the brooder.

3. In a brooder, a heat-distributing member, a hood about said member, curtains for inclosing the brooding space, rods arranged in sections for supporting said curtains about the periphery of said hood, each rod being hinged at one end to be swung outwardly to remove the curtain sections quickly from inclosing position, and means for securing the free end of said rods in 75 closed position.

4. In a brooder, a heat-distributing member, a hood about said member, and means on the edge of said hood adjustable in direction radiating from the hood, whereby 80 the brooding space within said hood may be extended.

5. In a brooder, a heat-distributing member, a hood about said member, and adjustable plates arranged about the edge of said hood by the positioning of which the area 85 of the brooding space beneath the hood may be varied.

6. In a brooder, a heat-distributing member, a hood about said member having its 90 periphery outwardly and downwardly inclined, adjustable members supported on said periphery for varying the area of the brooding space, in combination with peripheral curtains on said members for enclosing said brooding space, and means 95 whereby the curtains may be swung open to expose the interior of the brooding space.

7. In a brooder, a heat-distributing member, a hood about said member having its 100 periphery outwardly and downwardly inclined, adjustable members supported on said periphery for controlling the area of the brooding space, in combination with peripheral curtains on said hood, pivoted rods 105 for supporting said curtains, each of said rods being adapted to be swung out on its pivot ends to quickly remove its curtain sections from inclosing position.

In testimony whereof I affix my signature. 110

MARY CHASE BARON.
